UNITED STATES PATENT OFFICE.

WILLIAM M. VENABLE, OF PITTSBURGH, PENNSYLVANIA, ASSIGNOR TO BLAW-KNOX COMPANY, A CORPORATION OF NEW JERSEY.

BIN.

Application filed October 20, 1922. Serial No. 595,727.

To all whom it may concern:

Be it known that I, WILLIAM MAYO VENABLE, a citizen of the United States, residing at Pittsburgh, in the county of Allegheny and State of Pennsylvania, have invented certain new and useful Improvements in Bins, of which the following is a specification.

The present invention relates to bins useful for storing materials in bulk; and it is concerned both with the general construction of the bin, and with its adaptation, when desired, to equipment for delivering its contents in definite quantities or charges.

One important object of the invention is to simplify, strengthen, and lighten the construction of the bin, and to minimize the structural material required and the total cost of manufacture and installation. A further aim is to economize space and minimize the height of the structure in cases where the bin is equipped with subjacent charge or batch-measuring means (e. g., such as that disclosed in the application of

Allert F. Garlinghouse and William M. Venable, Serial No. 539,391, filed in the United States Patent Office February 27, 1922, and assigned to the assignee of this application) by arranging measuring means

and supporting framing in the same headroom. Another object is to provide a bin construction with a discharge gate arrangement such that charges of different kinds of materials may be drawn from the bin and measured synchronously, to be subsequently discharged properly portioned.

How these and other advantages can be realized through the invention will become apparent from the description hereinafter of the best embodiments known with particular reference to their adaptation and use for storing and dispensing materials for concrete,—such as broken or crushed stone, pebbles or gravel, cinders or slag, sand, etc.

In the drawings; Fig. 1 is a side elevation of a bin conveniently embodying my invention, equipped with measuring means such as disclosed in the above-mentioned application Serial No. 539,391.

Fig. 2 is a view from the left of Fig. 1, with the upper portion of the structure in

section as indicated by the line 2—2 in that figure.

Fig. 3 is a general plan view.

Fig. 4 is a fragmentary view illustrating the construction of the bin shell, with parts in section as indicated by the line 4—4 in Fig. 2.

Fig. 5 is another fragmentary view illustrating the construction of the bin shell, with parts in sections as indicated by the line 5—5 in Fig. 2.

Fig. 6 is a detached side view of one of the transverse bin frames.

Fig. 7 is a view similar to Fig. 6 illustrating a modification of the frame shown in Fig. 6, and indicating an application of the bin shell or lining different from that shown in Figs. 1—5.

The structure illustrated in Figs. 1 to 6 comprises a bin proper or shell for containing the materials to be stored, that is supported and held in shape by framing of structural steel, spanned between lateral supports suitably separated to afford space for a truck to drive between them beneath the bin. As shown (Figs. 1 and 2), rows of steel columns or posts 10 support horizontal girders 11, and on the latter rest transversely extending sustaining frames 12, (Figs. 2 and 6) of trussed construction, and of general V or U shape, that are braced and spaced apart by angle bars 13, 14, 15 extending lengthwise along the top edge of the bin and at intermediate points in its height. The trough-like container shell (see Figs. 1, 2 and 3) comprises a lining 16 (here of longitudinally extending planks) resting on and secured to the transverse frames 12, and end bulkheads 17 (of vertical planking) mounted on the lining and securely held in place by external and internal ledges 18, 19 (likewise of wood) fastened to the lining (see also Fig. 4).

As here shown, the end bulkheads 17 are additionally stiffened and held by angle bars 20 extending along their upper edges and secured to the end frames 12; by external horizontal wales 21, (see also Fig. 5) at intermediate points in their height; by upright internal angle bars 22, secured to the frames 12 and to the transverse top edge

angle bars 20 at their upper and lower ends, respectively; and by horizontal angle bars 23 extending lengthwise over the bin and secured at their ends to the top angle bars 20. As shown, the bin is divided into two compartments by an internal longitudinal partition 25 formed by vertical plank whose lower ends are bolted between longitudinal angle bars 26 fastened to the bin frames 12, 10 and whose upper ends are held between the longitudinal angle bars 23. The partition 25 is further stiffened with longitudinal members 27 bolted to it at either side. At suitable intervals in its length, angle bar 15 stays 28 extend transversely across the top of the bin, being secured to the corresponding transverse frame (or frames) 12 at their ends and at intermediate points to the angle bars 23, so as to keep the portion 25 properly in line.

Referring, now, more especially to Figs. 2 and 6, it will be seen that from a structural point of view each of the transverse truss frames 12 of the shell-sustaining frame structure may be regarded under two aspects.

Under one aspect, each of the frames 12 may be regarded as composed of two inclined triangular trussed sustaining members resting on the supports 10, 11 at their obtuse "intermediate" lower corners 30, and braced against rocking inward or outward relative to one another by being connected together or united at their acute lower corners or ends 31 and by the interconnecting transverse member 32. Under this aspect, the external sides or chord members of these inclined triangular trusses consist of the pairs of angle bars 33, 34, 35, and 36 (which last extends all the way across from one obtuse corner 30 to the other), and the remaining double angle bar members 37, 38, 39 and 40 serve as internal bracing against the various stresses to which the sides are subjected at intermediate points in their length,—while the member 41 braces the parallel members 36 and 32 the one relatively to the other.

Or, under another aspect, the bin framework as a whole may be regarded as composed of a straddling lower structure (including the lateral supports 10, 11) with transverse beam truss members, plus inclined triangular cantilever truss members secured to the ends of said beam members and upstanding from them. Under this aspect, the transverse beam truss comprises the members 32, 36 as upper and lower chords, with the members 39, 40, 35, and 41 as internal bracing; while the upstanding cantilevers comprise the members 34, 33, and 37, 38. The members 39 are in a manner common to beam and cantilever frame members.

For convenience in handling, the frames

12 will usually be built and riveted up according to the "three part" theory just described; that is to say, the two cantilevers and the beam will be riveted up and shipped separate (with the members 39 forming part of the beam), and only assembled and bolted together as one unit by the erecting force on the job.

Referring, now, more especially to Fig. 2, it will be seen that in the construction of Figs. 1 to 6, the planking 16 and the steel plating 42 that form the bottom of the bin shell rest on the frame members 32, while the planking 16 that forms the sides of the bin shell rests on the frame members 34 and (when the shell is carried to the full height shown) on prolongations of the members 33 beyond their connection with the members 34 at the upper corner of the triangular side trusses. Accordingly, the members 32 and 34 are made of sufficient depth to have ample beam strength for resisting the bending stresses due to the corresponding shell walls and the distributed load imposed by the bin contents. There is no difficulty in arranging the members 34 with suitable slope to enable the bin sides to feed the contents between the posts 10, to the rows of bottom openings in the plating 42 near the center of the bin, one row at each side of the partition 25.

As shown in Figs. 2 and 6, the length of the members 32 and the width of the bin at the bottom are less than the span between the posts 10 and the length of the horizontal trusses whose lower chords are the members 36. On the other hand, the top of the bin is wider than the span between the posts 10. Under all conditions of loading, the weight is transmitted to the lateral supports 10, 11, through the members 39 and 33, which are always in compression as struts. The members 35 are generally in tension as stays, and the member 41 generally in compression as a strut. When the bin is partially loaded with a pile in the middle, principally on the bottom, the weight is transmitted almost entirely through the members 39, and the members 32 are in compression. Under this condition, therefore, the behavior of the structure approximates the "three part" theory explained above. When, on the other hand, the bin is further filled, the outward pressure of its contents on the sides gradually increases the stress in the members 33, until when the bin is heaping full they carry most of the load. Under this latter condition, the members 32 act in tension to prevent the sides from swinging outward, and the behavior of the structure rather approximates the "two part" theory explained above. Under an intermediate condition of loading, the member 32 will be practically unstressed except for the bending due to the superincumbent deadweight of material: in

this case, the "balance" of the bin as a whole and of its structural halves over the posts 10 (which generally is only roughly approximate) becomes very close.

6 From Figs. 2 and 6, it will be seen the structure is transversely "sway braced" against wind pressure by coaction of the members 40 with angle bar members 43 connected bracketwise between the posts 10 and 10 the gusset plates 44 by which the lower ends of said members 40 are connected to the members 36. Longitudinally, the structure is sway-braced against wind pressure by angle bar members 45 connected between the 15 upper and lower ends of adjacent posts 10.

Referring, now, to Figs. 2 and 6, and regarding the straddlingly mounted bin in its entirety, it will be found to present a simpler and more unitary structural aspect than 20 appears in the foregoing piecemeal analysis.

In this light, it will be seen, the structure consists essentially of lateral supporting means extending substantially to the top of the bin at either side, and composed of the 25 columnar substructures 10, etc., with the strut members 33 secured thereto. These lateral supporting means 10, 33 are interconnected by the members 36 spanned between them,—or, indeed, by the girder members 30 412 in their entirety. The horizontal member is braced to the lower portions 10 of the lateral supporting means by the members 43; and to their upper portions 33 by the members 34, 35,—or, if the girder member 35 412 as a whole be considered, by the members 34 alone. The flat bottom 42 of the trough-like containing shell is secured to and sustained by the deep horizontal girder 412, and its sloping sides secured to the sloping members 34.

In a sense, the members 33 and 34 (with their interconnecting members 37, 38, and even 39 and 40) may be regarded as together constituting the upper portions of the lateral supporting means interconnected by the member 412; likewise, the members 10, 11, 46 43 together may be regarded as their lower portions.

The outflow or discharge of material from 50 the bottom openings of the bin is controlled by gates 46, which run between plate hangers 47 bolted to the bottom plates 42, on rollers 48 resting on angle bar tracks 49 secured to said plates 47. These hangers 47 also support depending charge-measuring containers or hoppers 50 and 51 made up of vertically telescoping sections, and adjustable in capacity according to the amounts and relative proportions of materials that it may be desired to draw from each compartment of the bin. Except for the duplication or extension required by the division of the bin into compartments and the provision of two separate openings in each gate 46, so that when 55 opened it acts to fill the two corresponding

hoppers 50 and 51 concurrently with the different materials from the two compartments, the arrangements and operation of bottom plates 42, gates 46, hangers 47, and hoppers 50, 51, etc., are entirely similar to 70 those of the application above referred to. As shown, there are four sets of double gates 46 and corresponding hopper pairs 50, 51, etc., one set for each interval between the frames 12. For each gate 46, accordingly, 75 there is an operating lever 53 hanging down from a fulcrum 54 on the longitudinal lateral angle bar 14 to within reach from the ground, and connected to the gate by a link rod 55; while the latch actuating cables or 80 chains for the self-closing counterweighted downward swinging discharge doors 56, 57 of the hoppers 50, 51 are connected together to a common cable or chain 58 similarly hanging down from a pulley 59 on the adjacent frame 12.

If, therefore, for instance, the small bin compartment is filled with sand and the large one with crushed stone, and it is desired to supply and convey to a mixer a 90 batch comprising 8 cu. ft. of sand and 12 cu. ft. of stone, to be mixed with 4 cu. ft. of cement (for a 1: 2: 3: mixture by volume), all that is necessary is to set a pair of hoppers 50 and 51 to hold 8 cu. ft. and 12 cu. ft. respectively.

To open and close, the gate 46 here shown moves crosswise of the bin partition 25, substantially in the line of its openings. Then operation of the corresponding gate 46 will 100 fill both hoppers 50 and 51 at the same time, and they may afterward be discharged at the same instant into the compartment of a truck driven below. In the case of a truck having several compartments, moreover, all 105 may be filled at once with variously proportioned charges without the truck being moved at all.

From Figs. 1 and 2, it will readily be seen that the vertical extent or depth of the bin 110 framing 12 below its bottom (represented by the height of the transverse truss beams) is utilized for two different purposes: to accommodate the measuring hoppers 50, 51, and to give substantial depth to the vertical 115 trussing that transmits the weight of the loaded bin to the lateral supports 10, 11. Thus, on the one hand, the posts 10 need be no longer than the headroom required for trucks; while, on the other hand, the transverse truss beams can be (and preferably are) made of the full depth of the hoppers 50, 51 when extended for maximum capacity, without the total height from the ground to the bin bottom being any more than is required to assure the necessary headroom for trucks below the hoppers. Owing to the ample depth of framing beneath the bin thus made possible, to the partial balance of the bin when heavily loaded, as already ex- 120 125 130

plained, and to various other features of the supporting structure, the total amount of steel that is required to sustain a given quantity of material in the bin at a height where it can be fed by gravity is surprisingly small.

Fig. 7 illustrates a bin construction more specially suitable and advantageous in cases where measuring hoppers are not to be used. Here, it will be seen, the members 33 and 36 (shown as I beams or channels) receive the plank lining, instead of the members 34 and 32, and are therefore the members of depth to resist bending stresses from the distributed load imposed by the contents of the bin. The other members 34, 32, etc., of the frames 12 are inside the bin instead of outside; so that for frames 12 of the same over-all dimensions, the bin capacity is much greater than in Fig. 1. Structurally, the framing 12 presents the same double aspect as in the Fig. 1 bin construction; and the variations of stress in the several members with variations of loading are of the same sort.

It will be understood, of course, that besides admitting of many minor changes like variation in length of the bin or of the number of frames 12, replacement of wood planking with steel plating in the construction of the shell, etc., the invention can be carried out, and its advantages realized to a greater or less degree, in a great variety of forms and modifications.

36 I claim:

1. A straddlingly mounted bin including supports separated to afford passage for vehicles between them under the bin, a containing shell, and sustaining framing for said shell comprising inclined members resting on said supports at an intermediate point in their length and braced together against rocking on said supports.

2. A straddlingly mounted bin including supports separated to afford passage for vehicles between them under the bin, a containing shell, and sustaining framing for said shell comprising inclined members resting on said supports at an intermediate point in their length and connected together at their lower ends, and a transverse member interconnecting said inclined members to brace them against rocking on said supports.

3. A bin including supports; framing comprising inclined sustaining members resting on said supports at an intermediate point in their length and connected together at the lower ends, with transverse interconnection above said lower ends to brace them together; and a containing shell with sides and bottom carried by said inclined members and said interconnection, respectively.

4. A bin including supports; framing comprising inclined triangular sustaining trusses resting on said supports at one cor-

ner of each and connected together at another corner, with transverse interconnection to brace them together against rocking on said supports; and a containing shell with sides carried by inclined sides of the trusses and bottom carried by other frame members.

5. A bin comprising U shaped transverse truss frames, and a containing shell with sides and bottom carried by chord members of said truss frames.

6. A bin including supports, framing comprising beams extending between said supports and upstanding cantilevers secured to the ends of said beams, and a containing shell with sides carried by said cantilevers and bottom carried by said beams.

7. A bin including supports, framing comprising trussed beams extending between said supports and upstanding triangular cantilever trusses secured to said beams, and a containing shell with sides and bottom carried by chord members of said trusses.

8. A bin including supports, a containing shell, triangular upstanding cantilever trusses for sustaining the sides of said shell, and transverse truss beams for sustaining the bottom of said shell comprising lower chords extending between said supports and interconnecting the lowermost corners of said cantilever trusses, upper chords interconnecting the other lower corners of said cantilever trusses, and bracing means for preventing collapse.

9. A bin frame including a bottom truss beam adapted to rest on spaced supports and comprising upper and lower chords, struts interconnecting their ends, and bracing means for preventing collapse; and cantilever trusses upstanding from said bottom truss and comprising upper and lower chord members connected to the ends of its corresponding chords; a chord member of each of the aforesaid trusses being adapted to act as a beam for sustaining a corresponding wall of the bin shell and the distributed load imposed by the bin contents.

10. A bin frame including a bottom truss beam adapted to rest on spaced supports and comprising upper and lower chords, struts interconnecting said chords at ends and middle, and stays connecting the ends of the upper chord with the middle of the lower chord; and cantilever trusses upstanding from said bottom truss and comprising upper and lower chord members connected to the ends of its corresponding chords and connected together at their upper ends.

11. A charging bin comprising a containing shell, a frame structure for said shell extending substantially below it, with room for a vehicle underneath and charge measuring means accommodated in the extent of the frame structure below the shell.

12. A charging bin including a contain-

- ing shell, means for supporting said shell comprising subjacent beams with room for a truck therebeneath, and charge measuring means accommodated in the depth of said beams.
13. A charging bin including a containing shell, vertically trussed supporting means for said shell extending substantially therebelow, with room for a vehicle underneath, and charge measuring containers accommodated in the extent of the truss structure below the shell.
14. A charging bin including a containing shell, means for supporting said shell from beneath comprising a straddling structure with transverse members of substantial depth below the shell and room for a vehicle beneath said members, and charge measuring means beneath said shell accommodated in the depth of said transverse members.
15. A charging bin including a containing shell with sloping sides; supporting means for said shell including lateral supports, and sustaining members inclined in conformity with the slope of the bin sides resting on said supports at an intermediate point in their length and extending substantially below the bottom of the shell; and charge measuring containers accommodated in the extent of said members below the bottom of said shell.
16. The combination with a bin divided into compartments, of means for controllably discharging material from said compartments, measuring means receiving the discharge from the respective compartments, said measuring means being separately adjustable to vary the proportions of ingredients from them in a batch, and means separate from said bin-discharging means for controlling the discharge from said measuring means.
17. The combination with a bin divided into compartments, of a common gate controlling the discharge from said compartments, measuring means receiving the discharge from the respective compartments separately adjustable to vary the amount drawn from each compartment, and means for concurrently discharging said measuring means operable independently of said gate.
18. The combination with a bin divided into compartments, of horizontally moving gate means at the bin bottom for discharging material from the compartments, charge measuring containers receiving the discharge from said gate means vertically adjustable in capacity independently of one another, and means at the bottoms of said containers for controlling their discharge.
19. The combination with a bin divided into compartments, of a common discharge gate having separate openings for said compartments and movable in the line of said openings to open and close, subjacent charge measuring containers receiving the discharge and adjustable in capacity independently of one another, and means at the bottoms of said containers for controlling their discharge.
20. A bin construction comprising, in combination, a containing shell, a U-shaped supporting truss frame for the shell, and separated lateral supports at the base of the truss frame.
21. A bin construction including parts constituting a containing shell and a trough-like supporting frame composed of interconnected side and bottom members so disposed that when the bin is lightly loaded bottom members are substantially under compression and when heavily loaded are substantially under tension and afford support for side members.
22. A bin construction comprising, in combination, a shell and a supporting frame composed of side and bottom members connected so that the outward thrust on one side member is translated by a bottom member into an inward pull on the other side member, thereby producing substantially balanced load conditions.
23. A straddlingly mounted bin with passage for vehicles underneath, comprising supporting means extending substantially to the top of the bin at either side, and a horizontal girder spanned between such supporting means and sustaining the bin bottom.
24. A straddlingly mounted bin with passage for vehicles underneath, comprising supporting means extending substantially to the top of the bin at either side, a deep girder spanned between such supporting means and sustaining the bin bottom, and means bracing said girder to the lower portions of said supporting means.
25. A straddlingly mounted bin with passage for vehicles underneath, comprising supporting means extending substantially to the top of the bin at either side, a horizontal girder spanned between such supporting means at an intermediate point in their height, and a trough-like containing shell conforming to the space between said supporting means above said girder.
26. A straddlingly mounted bin with passage for vehicles underneath, comprising supporting means extending substantially to the top of the bin at either side, and a horizontal member interconnecting said supporting means at a level affording headroom beneath, with braces extending from said horizontal member to said supporting means.
27. A straddlingly mounted bin with passage for vehicles underneath, comprising supporting means extending substantially to the top of the bin at either side, and a horizontal member interconnecting said support-

6
ing means at a level affording headroom beneath, with braces extending from said horizontal member to the upper and lower portions of said supporting means.

5 28. A straddlingly mounted bin with lateral supports separated to afford passage for vehicles between them under the bin, and comprising outer members extending substantially to the top of the bin, a horizontal member interconnecting said outer members, and a trough-like containing shell, with means bracing said horizontal member to the upper portions of said outer members.

10 29. A straddlingly mounted bin with lateral supports separated to afford passage for vehicles between them under the bin, and comprising outer members extending substantially to the top of the bin, a horizontal member interconnecting said outer members, members sloping inward from the upper por-

tions of said outer members to said horizontal member, and a trough-like containing shell with sides and flat bottom secured to said sloping members and said horizontal member, respectively.

25 30. The combination with individual material supply compartments, of discharge control means therefor having actuating mechanism for concurrently discharging material from said compartments, subjacent charge measuring containers receiving the discharge and adjustable in capacity independently of one another, and means separate from the aforesaid discharge controlling means for controlling the discharge ~~at~~ from said measuring containers.

In testimony whereof, I have hereunto signed my name.

WILLIAM M. VENABLE.
